Application September 4, 1952, Serial No. 21,334

Term of patent 14 years

(Cl. D87—5)

To all whom it may concern:

Be it known that we, Jack Brier, residing at Merion, in the county of Montgomery, State of Pennsylvania; E. Malcolm Belber, residing at Smyrna, in the county of Kent, State of Delaware; Morton Kolson, residing at Havertown, in the county of Montgomery, State of Pennsylvania; and John H. Walter, residing at Grosse Pointe, in the county of Wayne, State of Michigan, citizens of the United States, have invented a new, original, and ornamental Design for an Article of Luggage, of which the following is a specification, reference being had to the accompanying drawings, forming a part hereof.

Figure 1 is a side elevational view of an article of luggage showing our new design.

Figure 2 is a top plan view of an article of luggage showing our new design.

Figure 3 is an end elevational view of an article of luggage showing our new design.

Figure 4 is a bottom plan view of an article of luggage showing our new design.

Figure 5 is a fragmentary, enlarged perspective view of the handle portion of an article of luggage showing our new design.

We claim:

The ornamental design for an article of luggage, substantially as shown.

JACK BRIER.
E. MALCOLM BELBER.
MORTON KOLSON.
JOHN H. WALTER.
